US00D534708S

(12) United States Design Patent (10) Patent No.: US D534,708 S
Helbing et al. (45) Date of Patent: * Jan. 9, 2007

(54) PANTS

(75) Inventors: Luke H. Helbing, Chicago, IL (US);
Joshua J. Coenen, Chicago, IL (US)

(73) Assignee: Game Bibs, Inc., Chicago, IL (US)

() Term: 14 Years

(21) Appl. No.: 29/223,077

(22) Filed: Feb. 8, 2005

(51) LOC (8) Cl. 02-02

(52) U.S. Cl. D2/742; D2/857

(57) CLAIM

The ornamental design for pants, as shown and described.

DESCRIPTION

FIG. 1 is a front perspective view of pants showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dashed lines shown directly on the surface of the claimed article, throughout the views, are understood to represent stitching.

The broken lines showing a human figure in FIG. 1 is for environmental purposes only and forms no part of the claimed design.

1 Claim, 5 Drawing Sheets
